UNITED STATES PATENT OFFICE.

ERNEST BOCCINO, OF NEWARK, NEW JERSEY, ASSIGNOR OF ONE-THIRD TO SILVIA TOLINO, OF NEWARK, NEW JERSEY.

DESIGN FOR A CLOWN AND ANIMAL TOY.

Application filed April 21, 1926. Serial No. 17,365. Term of patent 3½ years.

To all whom it may concern:

Be it known that I, ERNEST BOCCINO, a citizen of the United States, residing at Newark, in the county of Essex and State of New Jersey, have invented a new, original, and ornamental Design for a Clown and Animal Toy, of which the following is a specification, reference being had to the accompanying drawing, forming part thereof.

The figure is a perspective view of the clown and animal toy.

I claim:

The ornamental design for a clown and animal toy, as shown.

ERNEST BOCCINO.
